UNITED STATES PATENT OFFICE.

JOHN T. H. PAUL, OF CHICAGO, ILLINOIS, ASSIGNOR TO E. GOLDMAN & COMPANY, OF CHICAGO,
ILLINOIS, A CORPORATION OF ILLINOIS.

WASHING-MACHINE.

No. 876,356.

Specification of Letters Patent.

Patented Jan. 14, 1908.

Application filed August 6, 1906. Serial No. 329,316.

To all whom it may concern:

Be it known that I, JOHN T. H. PAUL, a citizen of the United States, residing at Chicago, in the county of Cook and State of Illinois, have invented a new and useful Improvement in Washing-Machines, of which the following is a specification.

My invention relates particularly to machines for use in cleansing filtering-material, such as is commonly used in filters for filtering liquors.

My primary object is to provide a machine having improved means for circulating the cleansing-fluid and the filter-mass, thereby insuring more complete cleansing of the filter-mass and increasing the capacity of the machine.

The invention is illustrated in its preferred embodiment in the accompanying drawings, in which—

Figure 1 represents an end elevational view of my improved washing-machine; Fig. 2, a vertical longitudinal sectional view of the same; Fig. 3, a broken plan view of the machine; Fig. 4, an enlarged broken, sectional view of the injector employed; and Fig. 5, a broken detail sectional view showing the manner in which an air-pipe employed enters the casing through the same connection as does the injector-pipe employed.

In the construction shown, A represents a casing supported on legs A¹ and equipped with a lid A² through which the charge of filtering-material may be thrown into the casing; B, an injector having a pipe B¹ joined by a connection B² to one end of the casing at or near the bottom of the casing; B³, an air-pipe which enters the casing through the connection B² and extends across the bottom of the casing; C, a rotary cylindrical screen having tubular trunnions C¹, C², journaled in the ends of the casing near the top of the casing; C³, a sprocket-wheel secured on the trunnion C², through the medium of which the screen C is rotated; C⁴, C⁵, overflow-pipes with which the tubular trunnions communicate; D, a fan, or propeller, having a shaft D¹ journaled in a bearing D² in one of the casing-ends, near the bottom of the casing; D³, a tubular housing, for the fan supported on bracket-arms D⁴ projecting inwardly from the end of the casing; D⁵, a conical deflector secured at the opposite end of

the casing and having its point projecting toward the fan and in axial alinement therewith; D⁶, a bracket having a bearing for the shaft D¹; D⁷, a pulley through the medium of which the shaft D³ is rotated; D⁸, a sprocket-wheel secured on the shaft D³ and joined by a sprocket-chain D⁹ to a sprocket-wheel D¹⁰ journaled on a stud D¹¹ projecting from the casing-end somewhat above and at one side of the shaft D¹; D¹², a sprocket-wheel formed integrally with the sprocket-wheel D¹⁰ and connected by a chain D¹³ with the sprocket-wheel C³; and E a plug in the bottom of the casing controlled by a rock-shaft E¹ and a lever E² in a well known manner.

The casing, or receptacle, A may be of any suitable form. Preferably it has a half-cylindrical bottom a, plane sides a¹ and a rectangular top a², of which the lid A² forms a part. The lid A² is joined by hinges a³ to the stationary section of the top and has its free lateral edge secured by locking means a⁴ of well known construction.

The injector B comprises an inner nozzle b; an outer nozzle b¹, whose outer end has a screw connection with the base portion of the nozzle b; a casing b² into one end of which the nozzle b¹ is screwed; a funnel b³ having screw connection with an intermediate portion of the nozzle b¹ and having openings b⁴ through which the induced flow of water may pass; and a water pipe b⁵ having connection with the casing b² through one side thereof. The pipe B⁵ has screw connection with the end of the casing b² which is opposite the nozzle. The lower end of the pipe B¹ is joined by a T-shaped union b⁶ to a pipe-section b⁷ which has screw connection with a collar b⁸ secured to the casing-end. The pipe B³ has screw connection with the outer end of the member b⁹, and comprises sections b⁹, b¹⁰, the latter of which extends through the tubular member b⁷ and into the casing, where it is provided on its lower side with outlets b¹¹ through which the air may escape into the water and the filter-mass therein. It will be understood that the water and the steam condensed therein enter the casing through the annular space b¹² between the pipe-section b¹⁰ and the pipe-section b⁷, as clearly appears from Fig. 5.

The details of construction of the rotary screen C, which serves as an eduction con-

duit through which the overflow may pass to the pipes C^4 , C^5 , may be of any suitable construction. The trunnion C^1 is contained in a bearing c , which constitutes also a bushing; and the pipe C^4 has connection with the bearing c . The trunnion C^2 extends through a bearing c^1 equipped with a packing-ring c^2 . The pipe C^5 is supported by a bracket c^3 , and is equipped at its upper end with an 10 inturned elbow c^4 into which the trunnion C^2 extends loosely.

The propeller D may be of any suitable construction. The bearing D^2 constitutes also a stuffing-box, being equipped with a 15 packing-ring d . As stated, the axis of the propeller is in alinement with the conical deflector, or spreader, D^5 ; and the axis of the tubular housing D^3 is likewise in alinement with the axis of the member D^5 .

20 The details of construction of the plug E , which may be opened to permit the filter-mass to be discharged from the receptacle, are of common construction and need not be described.

25 In operation, steam enters through the nozzle b and induces a flow of water through the pipe b^5 , the mingled streams entering the casing of the machine through the annular passage b^{12} . Power is imparted to the 30 propeller D through the medium of the pulley D^7 , and is communicated from the propeller-shaft to the screen C through the medium of the sprocket-wheels and chains. The propeller operates to force the water and 35 filter-mass through the tubular housing D^3 and against the conical spreader D^5 , which divides the current, causing it to circulate back in all directions to the rear of the funnel D^3 . The mass is kept open and matting 40 prevented by air currents injected through the openings b^{10} of the section b^{11} of the pipe B^8 .

The machine described is of simple construction, is easily operated and admirably 45 adapted to its purpose. Experience has demonstrated that it will operate to more effectually cleanse filtering-material than the

known machines, and that it possesses increased capacity.

What I regard as new, and desire to secure 50 by Letters Patent, is:

1. In a machine of the character set forth, the combination of a casing, a spreader supported in the casing, and a propeller operating to propel the filter-mass and washing 55 fluid toward said spreader.

2. In a machine of the character set forth, the combination of a casing, a water-supply pipe communicating with the casing at one end thereof near the bottom of the casing, 60 a spreader connected with the same end of the casing at a higher point, a propeller arranged opposite said spreader, and an induction port communicating with the interior of the casing near the upper portion 65 thereof.

3. In a machine of the character set forth, the combination of a casing, a water-supply pipe connected therewith, a spreader supported at one end of the casing, a tubular 70 housing open at both ends supported at the other end of the casing in axial alinement with said spreader, and a rotary propeller in said housing, for the purpose set forth.

4. In a machine of the character set forth, 75 the combination of a casing, an injector-pipe equipped with an injector, a union connecting said pipe with the lower portion of the casing, an air-pipe extending through said union and into the casing and provided with in the casing with perforations, and an induction port connected with the upper portion of the casing.

5. In a machine of the character set forth, 80 the combination of a casing, a conical spreader in said casing and supported on one end thereof, a tubular housing supported on the other end of said casing, and a propeller in said tubular housing.

JOHN T. H. PAUL.
